[57] CLAIM

The ornamental design for a nut dish, as shown and described.

DESCRIPTION

FIG. 1 is a top perspective view of a nut dish showing my new design, with cover removed;

FIG. 2 is a top plan view thereof;

FIG. 3 is a front elevational view, the rear, left side, and right side elevational views being mirror images thereof;

FIG. 4 is a bottom plan view thereof; and,

FIG. 5 is a top perspective view thereof with cover, the bottom plan view of the cover being plain and unornamented.

FIG.1

FIG.2

FIG.3

FIG.4

FIG.5
